CAP

Frederick B. Miller, Montclair, N. J., assignor to
 Union Bag & Paper Corporation, Hudson Falls,
 N. J., a corporation of New Jersey

Application August 24, 1932. Serial No. 630,293

2 Claims. (Cl. 2—200)

The present invention relates to improvements for caps for personal wear and the primary objects are to provide a novel cap which can be manufactured inexpensively and with facility of 5 paper or other inexpensive flexible material, the cap being compactly folded when collapsed so that it will occupy minimum space for shipping or storage and will be capable of being easily and quickly unfolded and thus opened when ready 10 for use, the top of the cap being closed by flaps which are so folded that they conform substantially with the shape of the cap when it is opened and applied to the head of the wearer, the improved cap being particularly adapted for advertising purposes since it may be manufactured 15 from a strip of paper which may have advertising matter readily and inexpensively printed thereon previous to the making of the caps therefrom so that the printed advertising matter 20 will appear in appropriate positions on the finished caps.

In the accompanying drawing:

Fig. 1 is a side elevation, partly in section, of a cap made in accordance with the present invention, the cap being shown in folded or collapsed condition;

Fig. 2 is a top plan of the improved cap in unfolded or opened condition;

Fig. 3 is a transverse vertical section through 30 the unfolded or opened cap, taken on the line 3—3 of Fig. 2;

Fig. 4 is a transverse section through the folded or collapsed cap, taken on the line 4—4 of Fig. 1; and

Fig. 5 is a perspective view of the cap in substantially the form which it assumes when applied to the head of the wearer.

Similar parts are designated by the same reference characters in the several figures.

The improved cap, which is made preferably 40 from a strip or sheet of paper of the kind commonly used in the making of paper bags, or other suitable flexible or foldable material, comprises a tubular body portion 1 of a suitable diameter 45 to fit around the head of the wearer, the lower edge of this body portion being turned inwardly to form a sweat band 2 and also to stiffen the lower edge of the body portion and reinforce it against splitting or tearing, the upper end of 50 the tubular body portion being closed by a pair of flaps 3 which are turned inwardly from the front and rear of the body portion, respectively and side flaps 4 which are turned inwardly from the respective sides of the body portion and are 55 pasted to the inner ends of the flaps 3 and to one

another. The flaps 3 are joined to the sides of the body portion along fold lines 5 which converge to points 6 at the front and back respectively of the cap, the central longitudinal elongation thus produced in the top of the cap bringing it into approximate conformity with the curvature of the wearer's head at the front and back and thus enabling the top of the cap to readily accommodate itself substantially to the shape of the wearer's head when the cap is applied thereto. The cap may have advertising or other printed matter applied thereto as indicated at 7 and 8 and may be printed with an ornamental design 9 such, for example, as that shown.

When the cap is collapsed or folded it will have the appearance and form shown in Figs. 1 and 4, the sides of the body portion 1 being then flattened against one another and the top of the cap lying closely at one side of the body portion 60 and being connected thereto by the fold line 10, as shown most clearly in Fig. 4. While the cap is thus folded or collapsed, it will occupy minimum space for shipping or storage. When the cap is to be used, it is opened by spreading apart 65 the sides of the body portion 1 and sweat band 2, and as this portion of the cap is thus opened, the top portion of the cap will swing into position above the body portion, it swinging about the fold line 10 so that this side of the body portion assumes an upright position substantially parallel 70 with the opposite side of the body portion, substantially as shown in Fig. 3, and the folds 3 at the front and back of the cap will assume a more or less curved form substantially as shown in 75 Fig. 5 and thus conform substantially with the shape of the wearer's head at the front and back thereof.

The improved cap is preferably made from a tube of paper of appropriate diameter, the sides 80 of the tube at one end thereof, while the tube is in flattened form, being spread apart to produce the so-called diamond make in the manufacture 85 of ordinary satchel bottom bags and forming the lateral flaps 3 which fold on the diagonal lines 90 5 which converge to the points 6 which coincide with the flattened edges of the tube, after which the flaps 4 are folded inwardly over the flaps 3 on one another and are pasted together as in an ordinary satchel bottom bag.

The cap may be perforated at any suitable part 95 or parts thereof for ventilating purposes. In Fig. 5 six such perforations 11 are shown, four 100 in the top and two in one side of the cap. These 105 perforations may be produced by punching 110

through the cap, while folded, at the four points at which perforations are shown in Fig. 1.

The improved caps may be manufactured inexpensively on an ordinary bag making machine of well known form for making satchel bottom bags, as for example is shown in Letters Patent No. 407,794, granted July 30, 1889, and No. 417,346, granted December 17, 1889, to C. B. Stilwell, with the exception that the paper tube from which the bags are made is formed without pleats in its edges, in consequence of which the lateral flaps 3 will extend to the points 6 coincident with the unpleated folded edges of the tube. The advertising, ornamental design or other matter appearing on the finished caps may be inexpensively printed on the strip from which the tube is made, previous to the folding and finishing of the caps, substantially as is done in the making of printed bags from previously printed bag strips.

Caps made in accordance with the present invention may be manufactured very inexpensively from ordinary bag paper or similar inexpensive material so that they may be discarded when soiled, and because of the inexpensiveness of the caps, they may be printed with any desired advertising matter and distributed at small cost, thus serving as an advertising medium.

I claim as my invention:

1. A cap comprising a tubular body composed of foldable material one end of which is turned in around its edge to form a band to fit around the head of the wearer and the other end of which is closed by flaps formed by inward extensions of the sides and edges of the tubular body, the flaps extending from the edges of said body being folded with respect to the body on diagonal lines which converge to points located substantially at the inner edge of said inturned end at the front and back of said body.
2. A cap comprising a flat tubular paper body one end of which is turned in around its edge to form a band and a top composed of flaps formed by extensions of the sides of said body, certain of said flaps being folded on lines which converge toward the opposite folded edges of the tubular body and to points located substantially at the inner edge of said inturned end of the body and the top being joined to one side of the tubular body by a fold line which is located substantially at the inner edge of said inturned end of the body and enables the top to collapse flatwise against the flat tubular body.

CERTIFICATE OF CORRECTION.

Patent No. 1,926,912.

September 12, 1933.

FREDERICK B. MILLER.

It is hereby certified that the residence of the assignee in the above numbered patent was erroneously described and specified as "Hudson Falls, New Jersey," whereas said residence should have been described and specified as Hudson Falls, New York, as shown by the records of assignments in this office; and that the said Letters Patent should be read with this correction therein that the same may conform to the record of the case in the Patent Office.

Signed and sealed this 5th day of December, A. D. 1933.

F. M. Hopkins

(Seal)

Acting Commissioner of Patents.
